UNITED STATES PATENT OFFICE.

HOWARD M. BARBER, OF STONINGTON, CONNECTICUT, ASSIGNOR, BY MESNE ASSIGNMENTS, TO C. B. COTTRELL & SONS COMPANY, OF NEW YORK, N. Y., A CORPORATION OF DELAWARE.

CREASING MECHANISM FOR SHEET COLLECTING AND FOLDING MACHINES.

1,194,348.

Specification of Letters Patent. Patented Aug. 15, 1916.

Application filed November 15, 1913. Serial No. 801,293.

To all whom it may concern:

Be it known that I, HOWARD M. BARBER, a citizen of the United States, and resident of Stonington, in the county of New London 5 and State of Connecticut, have invented a new and useful Improvement in Creasing Mechanism for Sheet Collecting and Folding Machines, of which the following is a specification.

10 The object of this invention is to provide means for creasing folded signatures so that when the signatures are superposed or gathered and secured together, as by stapling, the magazine or book thus formed, 15 will lie open at any particular page.

A further object is to crease a signature which has been folded transversely of its travel, said crease being imparted to the folded signature at a predetermined distance 20 from its back or folded edge and parallel thereto.

25 A still further object is to reversely crease the so folded signature so that each leaf of the book or magazine formed from a collection of signatures will readily fold back either way along the crease thus formed.

30 A practical embodiment of the invention is represented in the accompanying drawings, in which,

35 Figure 1 is a view in side elevation of so much of a collecting and folding machine as will give a clear idea of my invention applied thereto. Fig. 2 is a vertical section taken within and adjacent to the farther side frame of the machine. Fig. 3 is a detail diagrammatic section taken centrally through the machine from front to rear. Fig. 4 is an enlarged detail section showing the parts in the position which they assume 40 when the first crease is being imparted to the folded signature. Fig. 5 is a similar view showing the parts in the position which they assume when the second or opposite crease is being imparted to the folded signature 45 along the line of the first crease. Fig. 6 is a detail face view of the creasing blade on the scale shown in Figs. 4 and 5, and Fig. 7 is a detail section showing a modified form of the first creasing roll.

50 The two side frames of the machines are denoted by 1 and 2. The web feed roll is denoted by 3, which roll is suitably mounted in the side frames 1 and 2. The pair of

55 rotary cutters 4 and 5 have their shafts 6 and 7 mounted in the side frames of the machine, which cutters are, in the present instance, shown as provided with three sets of coacting blades 8, 9, arranged to cut the web 10 into three sheets for each revolution of the cutters. 60

The sheet collecting cylinder 11 has its shaft 12 suitably mounted in the side frames of the machine, which cylinder is shown as being provided with three sets of grippers 13, 14, 15, with three intermediate collecting 65 surfaces. The collecting cylinder 11 is provided with three tucking blades 16, 17, 18, located intermediate the grippers 13, 14, 15, which blades are arranged to successively 70 coat every one and one-third revolutions of the collecting cylinder 11, with the floating folding jaw 19 carried by the rotary carrier 20, the shaft 21 of which is suitably mounted in the side frames of the machine. In the arrangement of the parts as herein shown, 75 the cylinder 11 collects four sheets cut from the web on each collecting surface and folds off the collected group of four sheets to the rotary carrier 20.

80 The cam mechanism for insuring the proper opening and closing of the collecting cylinder grippers, the folding off of the collected sheets to the floating folding jaws 19 and for controlling the floating of said jaws will not be specifically described here- 85 in as they may be of any well known or approved form and are not a part of the present invention, which invention is directed to the creasing of the folded signatures, the mechanism for which will now be described. 90

95 The shaft 22 of the delivery cylinder 23, is mounted in suitable bearings in the side frames 1 and 2 of the machine. This cylinder is provided with a set of grippers 24 arranged to take the folded signature from the folding jaws 19 of the rotary carrier 20 and deposit the signature after it has been slit longitudinally of its travel, into a plurality of smaller signatures. In the present instance, a portion of a pocketed carrier 25 100 is shown for receiving the signatures from the delivery cylinder 23. A shaft 26, mounted in spring-pressed bearings in the side frames of the machine, carries one or more slitting disks 27, arranged to coact with one or more circumferential grooves 28 in

the delivery cylinder 23, for slitting the folded signature into two or more sections as desired.

Creasing rolls 29, 30, have their shafts 31, 32, mounted in suitable spring-pressed bearings carried by the side frames of the machine. A creasing blade 33, works inwardly and outwardly in a slot 34 in the periphery of the delivery cylinder 23. This blade is guided in its movements by pins 35 passing through elongated slots 36 in the blade. The inner edge of this blade 33 is seated in a transverse holder 37 having studs rotatably mounted in the free ends of the arms 39, fixed to a rock shaft 40. This rock shaft is provided with a rocking arm 41 exterior to the delivery cylinder, which arm carries a stud or roller 42 arranged in position to be engaged by a fixed cam 43 for moving the creasing blade outwardly. A spring 44 on a rod 45 attached to the free end of the arm 41 and having a sliding engagement at 46, with the delivery cylinder, serves to normally move the creasing blade to the limit of its inward movement.

The first creasing roll 29 is provided with a groove 47 for receiving the outer edge of the creasing blade when it is moved outwardly to form the first crease in the folded signature. In Figs. 1 to 6 inclusive, this groove 47 is shown as located in a block 48 of yielding material seated in a suitable holder 49, and in Fig. 7, this groove is shown formed directly in the roll.

The second creasing roll 30 is provided with a fixed creasing blade 50 projecting slightly beyond the periphery of the roll, which creasing blade is arranged to enter the slot 34 when opposite the same, for imparting the second crease in the opposite direction along the line of the first crease.

A fixed cam 51 is located in position to engage the stud roller 52 on the rock lever 53 of the set of grippers 24, to open the grippers for receiving the folded signature from the rotary carrier 20, and a fixed cam 54 is arranged in position to engage the said stud roller 52, for opening the grippers to deliver the folded, creased and slit signature into the pocketed carrier 25.

The several rotary parts are interconnected to move at the desired relative speeds through a train of gearing 55, 56, 57, 58, 59, 60, 61, 62, 63, 64, 65.

In operation, the web as it comes from the press, passes over the feed roll 3, and from thence down between the rotary cutters 4, 5, where it is severed into sheets, which sheets are collected in groups of four on the three-way collecting cylinder 11, and successively folded off therefrom to the rotary carrier 20. This rotary carrier 20 transfers the folded group of sheets to the delivery cylinder 23, where the signature is slit longitudinally into the desired number

of sections and is creased transversely to its travel and parallel to the fold by the coaction of the movable creasing blade 33, with the groove 47 in the first creasing roll 29. As the signature continues its movement, it is creased inwardly along the line of the outward crease by the coaction of the fixed creasing blade 50, on the second creasing roll 30, with the groove 34 in the delivery cylinder. This reverse creasing of the signature adjacent to its folded edge and parallel thereto, will permit each of the leaves to be readily turned back and forth on the said reverse crease as a hinge, permitting the book or magazine formed from a signature or a collected group of signatures to be readily opened and when open, to lie flat at any particular portion thereof.

It is evident that various changes may be resorted to in the construction, form and arrangement of the several parts without departing from the spirit and scope of my invention; hence I do not wish to limit myself to the construction herein shown and described, but

What I claim is:

1. In a machine of the character described, means for folding a signature and means for creasing the signature parallel to the fold.
2. In a machine of the character described, means for folding a signature transversely of its travel and means for creasing the signature parallel to the fold.
3. In a machine of the character described, means for folding a signature and means for reversely creasing the signature parallel to the fold.
4. In a machine of the character described, means for folding a signature transversely of its travel and means for reversely creasing the signature parallel to the fold.
5. In a machine of the character described, means for folding a signature, a cylinder for receiving and carrying the folded signature to a predetermined point and means coacting with the cylinder for creasing the signature parallel to its folded edge.
6. In a machine of the character described, a cylinder for carrying a folded signature and means coacting with the cylinder for reversely creasing the signature parallel to its folded edge.
7. In a machine of the character described, means for folding a signature, a cylinder for receiving and carrying the folded signature to a predetermined point, a creasing roll and means carried by the cylinder and roll for creasing the signature parallel to its folded edge.
8. In a machine of the character described, a cylinder for carrying a folded signature, two creasing rolls and means carried by the cylinder and rolls for reversely creasing the signature parallel to its folded edge.
9. In a machine of the character described,

- a cylinder for carrying a folded signature, said cylinder having a creasing blade, and a creasing roll having a groove for receiving said blade to crease the signature parallel to its folded edge. 5
10. In a machine of the character described, a cylinder for carrying a folded signature, said cylinder having a transverse groove and creasing blade movable therein, a creasing roll having a groove for receiving said blade when moved outwardly and means for moving said blade outwardly to crease the signature parallel to its folded edge. 10
15. 11. In a machine of the character described, a cylinder for carrying a folded signature, said cylinder having a transverse groove and a creasing blade movable therein, two creasing rolls one having a groove 20 to receive said movable blade when moved outwardly and the other having a fixed blade for entering said groove in the cylinder when the movable blade is moved inwardly and means for moving said first named blade outwardly to form the first crease in the signature and inwardly to permit the opposite crease being formed in the signature along the line of the first crease. 25
12. In a machine of the character de-
- scribed, a cylinder having engaging means for carrying a signature to a predetermined point, a creasing roll and means carried by the cylinder and roll for creasing the signature. 30
13. In a machine of the character de- 35 scribed, a cylinder for carrying a signature, two creasing rolls and means carried by the cylinder and rolls for reversely creasing the signature.
14. In a machine of the character de- 40 scribed, a cylinder having engaging means for carrying a signature to a predetermined point, a creasing roll and means carried by the cylinder and roll for creasing the signature transversely of its travel. 45
15. In a machine of the character de- 50 scribed, a cylinder for carrying a signature, two creasing rolls and means carried by the cylinder and rolls for reversely creasing the signature transversely of its travel.

In testimony, that I claim the foregoing as my invention, I have signed my name in presence of two witnesses, this twelfth day of November, 1913.

HOWARD M. BARBER.
